RECEIVER ASSEMBLY

Oliver N. Lewis, New Haven, Conn., assignor to Olin Mathieson Chemical Corporation, a corporation of Virginia

Filed Oct. 2, 1958, Ser. No. 764,798

4 Claims. (Cl. 42—75)

The present invention is directed to firearms and deals in particular with gas operated weapons.

A particular feature of the invention is the provision of a novel receiver assembly in weapons of the above general class.

An additional feature of the invention is the provision of a receiver-trigger guard-slide arm arrangement which affords a minimum width across the receiver body.

A further feature of the invention is the provision of a firearm receiver assembly including a receiver having a pair of depending sidewalls, a trigger guard having a pair of guide tracks and a pair of slide arms movable upon the tracks wherein one sidewall, one slide arm and one track of each pair thereof are tiered vertically.

A firearm embracing certain features of the present invention may comprise a receiver having a pair of laterally spaced depending sidewalls, a pair of slide arms and a trigger guard including a pair of laterally spaced guide rails, the sidewalls of the receiver and the guide rails being spaced from one another, vertically, so as to provide support and sliding clearance for the slide arms, one slide arm and one guide rail of each pair thereof being disposed coplanar with the corresponding depending side wall of the receiver.

Other features and advantages of the invention will become more apparent from the succeeding specification when read in conjunction with the appended drawings, in which:

Fig. 1 illustrates a portion of a gas operated firearm utilizing the principles of the present invention with certain parts thereof broken away for clarity;

Fig. 2 is a vertical section of Fig. 1 as viewed in the plane of the line 2—2 and in the direction indicated;

Fig. 3 shows the slide arms in perspective; and

Fig. 4 is a perspective view of the trigger guard.

Referring now to the drawings, there is shown a wooden stock 10 having a cavity 11 for receiving and supporting a barrel receiver assembly indicated generally by the reference numeral 12.

A group of elements, hereinafter referred to as the receiver assembly, includes the receiver member 13 having a pair of depending sidewalls 14 and 16 respectively. The rear end of the receiver is mounted upon a boss 17 formed integral with a recoil block 18 in turn secured to the stock 10 by means of a screw 19 in generally the same fashion as shown and described in U.S. Patent 2,844,904, issued on July 29, 1958, to Wallace B. Butler.

The forward end of the receiver is connected to a barrel 21 in turn secured by means of a take-down screw to the stock in the manner disclosed and claimed in said Butler patent.

The receiver houses a bolt assembly 22 adapted to reciprocate within the receiver along the ways or keys 23, 24 and 26.

The bolt assembly, shown in the retracted or open position in Fig. 1, is actuated by a pair of slides or slide arms 27 and 28 each terminating at one end in a return bend portion defining ears 29 and 31 respectively.

2

The connection between the slides and the bolt assembly is accomplished by a pin 32 received in the slot 33 of the bolt assembly and the holes 34 and 36 of the slide arms.

5 The front ends of the slide arms are connected to a driving block 37 actuated by a gas piston (not shown) in well-known fashion. A finger piece 38 is provided upon slide arm 28 so that the slide may be actuated manually.

A trigger guard assembly, indicated generally by the 10 reference numeral 39, is shown secured at its rear end to a depending lug 41 formed on the recoil block 18 by means of a screw 42, while the forward end thereof is connected to the receiver 13 by means of a T-shaped key 43 which engages a mating slot in the receiver.

15 Pin 44 is effective to lock the trigger guard and the receiver against longitudinal relative motion. Note, in particular, that the guard assembly embraces a first pair of guides or rails 46 and 47 spaced apart at the rear end by the main body 48 of the trigger guard while the front 20 ends of the rails are stiffened by a block 49 having an inclined wedge-like surface 51 adapted to mate with a corresponding surface formed on the stock 10. The guard assembly also includes a second pair of guide rails 45 and 50 which are straddled by the ears 29 and 31.

25 A reference to Fig. 2 at this time will reveal a prime advantage of the present invention wherein it is apparent that the depending sidewalls 14 and 16 of the receiver are each tiered above and are coplanar with the side arms 28 and 27 respectively which are, in turn, tiered above 30 and are coplanar with the guide rails 47 and 46 of the trigger guard assembly.

Obviously, the slide bars are supported by and moved to and fro upon the rails 46 and 47. Note also that the slides are restrained laterally wherein the ears 29 and 35 31 straddle and slide along the outside surfaces of the guides 45 and 50, respectively.

35 From the viewpoint of the cavity 11 formed in the stock, within which the receiver assembly is disposed, the slide arms and the trigger guard rails 46 and 47 amount 40 to extensions of the receiver sidewalls 14 and 16 thus affording an exceedingly slim receiver assembly.

In prior art arrangements, the slides frequently straddle the receiver or are otherwise disposed outside the receiver sidewalls necessitating a thicker receiver section and a correspondingly heavier stock in the area of the receiver. In other prior art designs the slides are disposed inside the receiver and this arrangement also requires a wider receiver in order to accommodate the slides and the bolt.

45 Note that the tiering or vertically disposition of the sidewalls of the receiver, the slide arms and the trigger guard rails permits an absolute minimum width across the receiver body as evidenced by the dimension A in Fig. 2.

Obviously, a variety of modifications and arrangements can be devised in the present invention without departing from the spirit and scope thereof.

55 What is claimed is:

1. A firearm receiver assembly comprising a receiver, a pair of slide arms, and a trigger guard, said receiver having a pair of laterally spaced depending sidewalls and said trigger guard including a pair of laterally spaced 60 guide rails, the sidewalls of the receiver and the guide rails being spaced from one another, vertically, so as to provide sliding clearance for the slide arms, one slide arm and one guide rail of each pair thereof being disposed coplanar with the corresponding depending sidewall of the receiver and means for securing the assembly together to maintain said coplanar disposition.

2. The firearm receiver assembly of claim 1 wherein a second pair of guide rails are provided in the trigger guard for precluding lateral motion of the slide arms 70 with respect to the receiver.

3. A firearm receiver assembly comprising a receiver

having a pair of laterally spaced depending sidewalls, a recoil block for supporting the rear end of the receiver, a pair of slide arms, a trigger guard secured to the recoil block and including a pair of laterally spaced guide rails, the forward end of said trigger guard being rigidly connected to the forward end of the receiver, the sidewalls of the receiver and the guide rails being spaced from one another vertically so as to provide sliding clearance for the slide arms, one slide arm and one guide rail of each pair thereof being disposed coplanar with the corresponding depending sidewall of the receiver the connection between the trigger guard and the recoil block and the trigger guard and the receiver being operative to maintain the coplanar disposition of the sidewalls, slide arms and guide rails.

4. A firearm receiver assembly comprising a receiver having a pair of laterally spaced depending sidewalls, a recoil block for supporting the rear end of the receiver, a

pair of slide arms, a trigger guard secured to the recoil block and including a pair of laterally spaced guide rails, the forward end of said trigger guard being rigidly connected to the forward end of the receiver, the sidewalls of the receiver and the guide rails being so tiered vertically so that the slide arms ride on the rails, one slide arm and one guide rail of each pair thereof being disposed coplanar with the corresponding depending sidewall of the receiver said assembly being secured together to maintain the coplanar arrangement by means of the connection between the trigger guard, the recoil block and the receiver.
